UNITED STATES PATENT OFFICE

AMBROSE C. DE LANGE, OF KALISPELL, MONTANA

CARBURETOR

Application filed March 10, 1927. Serial No. 174,377.

This invention relates to carburetors for use primarily in conjunction with internal combustion engines.

One of the primary objects of the invention is to provide an atomizing carburetor constructed in such a manner that the fuel will be broken into particles of such fineness and combined and mixed with the air so thoroughly that combustion thereof when introduced into the engine will be instantaneous and perfect.

Another salient object of the invention is to provide a carburetor in which a predetermined quantity of fuel will be delivered relative to a predetermined quantity of air so that a proper mixture will be had for all speeds of engines.

A further object of the invention is to provide novel means for lifting the fuel and atomizing the same, said means including a novel arrangement of fuel tubes and an air pressure nozzle, means being provided for controlling and reducing or accelerating the pressure of the air at the nozzle for different qualities of fuel.

A further object of the invention is to provide a novel tube arranged in the air stream directly above the fuel outlets and air pressure nozzle, for breaking up the fuel into minute particles and combining the same with the compressed air and finally spreading the fuel in the nature of a fine atomized whirl directly in the path of the air stream.

A further object of the invention is to generally simplify carburetor construction, and to insure the proper operation of the carburetor and the proper mixing of the fuel and air and the turning of the fuel mixture into a fine atomized spray.

A still further object of the invention is to provide novel automatic means for controlling the flow of the fuel automatically according to speed of the engine, said means embodying a plurality of fuel outlet tubes of different diameters arranged adjacent to the compressed air outlet nozzle, the tubes terminating at different points relative to the nozzle, the tube of smallest diameter terminating nearest the nozzle, while the tube of greatest diameter terminating furthest from

the nozzle, whereby as the suction in the carburetor increases the different tubes will be brought into use.

A still further object of the invention is to provide a carburetor in which there will be no restriction of the inrush of air when the engine is on a full load by a Venturi tube or the like, the carburetor only restricting the flow of air at the throttle, which facilitates a quick acceleration of the engine.

With these and other objects in view, the invention consists in the novel construction, arrangement and formation of parts, as will be hereinafter more specifically described, claimed, and illustrated in the accompanying drawings, in which:

Figure 1 is a vertical section through the improved carburetor,

Figure 2 is an enlarged detail section through the novel fuel supplying device,

Figure 3 is a horizontal section through the carburetor taken on the line 3—3 of Figure 1 looking in the direction of the arrows,

Figure 4 is a side elevation of the improved carburetor drawn on a small scale,

Figure 5 is a detail side elevation drawn on an enlarged scale of a modified form of fuel supplying device,

Figure 6 is a top plan view of the novel Venturi tube, and

Figure 7 is a vertical section through the novel Venturi tube drawn on an enlarged scale.

Referring to the drawings in detail, wherein similar reference characters designate corresponding parts throughout the several views, the letter A generally indicates the improved carburetor which comprises a float chamber 10 having a fuel inlet 11 communicating with the lower end thereof. The float chamber 10 can be of any desired character and as shown the same is provided with a removable cover plate 12.

The flow of fuel through the fuel inlet 11 is controlled by a needle valve 13. This needle valve is in turn operated by a float 14 which can be of any desired construction or form. Any preferred mechanism can be used between the float and the needle valve for operating the valve for controlling the level

of the fuel in the chamber. As shown suitable bell cranks 15 are provided and these cranks are pivotally connected at their angles to the cover plate 12. The inner ends of the bell cranks are connected as at 16 to the stem 5 17 of the valve 13, while the outer ends of the cranks are connected as at 18 to the float. A spider 19 is carried by the float chamber and acts as a guide for the valve.

10 It can be seen that when the level of the fuel lowers in the chamber that the float will also lower and thus rock the bell cranks 15 and raise the needle valve 13, which will allow the entrance of a further supply of fuel to the float chamber. When the level 15 of the fuel reaches a predetermined height, the float will be raised causing the seating of the needle valve and the consequent stoppage of a further supply of fuel to the chamber.

20 At one side of the chamber 10 is arranged a vertical casing 20 which can be formed integral with or separate from the chamber 10. The upper end of the casing is provided with 25 a flange 21 for permitting the convenient connection of the carburetor with the intake pipe or manifold of an internal combustion engine. The lower end of the casing is provided with a lateral extension 22 in which is 30 rockably positioned a choker valve 23 which can be controlled in any desired way from a point distant from the carburetor. This choker valve functions substantially in the ordinary way for controlling the supply of 35 air to the carburetor.

Extending axially into the casing 20 from the lower end thereof is a fuel feed pipe 24. The lower end of this pipe is threaded as at 40 25 so as to permit the convenient connection thereof with the casing and the extreme lower end of the pipe is provided with a polygonal shaped head 26 for engagement with the bottom wall of the casing 20 and for facilitating the placing of the pipe in position in the casing. The bore of the pipe at its lower end 45 is reduced and provided with internal threads, for a purpose, which will be later described. This pipe is provided with a fuel inlet opening 27 above the reduced portion 50 of the bore of the pipe. The casing 20 is provided with a bore 28 which communicates with the fuel chamber 10 adjacent to the lower end thereof and when the fuel pipe 24 is threaded in its correct position the opening 55 27 will register with the way 28, which will allow the passage of the fuel from the float chamber into the fuel pipe. A suitable packing 60 gland 29 is provided for engaging the tube or pipe 24 above the opening 27 so as to prevent the leakage of the fuel around the sides of the pipe.

In accordance with this invention a compressed air receiving tube 30 is threaded into the lower end of the fuel pipe 24 and this tube extends through the upper end of the

pipe and is provided with a removable nozzle 31. It is to be noted that the upper end of the pipe 24 is provided with a shoulder 32 for intimate contact with the outer surface of the compressed air receiving tube. The lower end of the tube 30 is provided with a polygonal head 33 for engagement with the head 26 on the fuel pipe. A compressed air feed pipe 34 is connected with the lower end of the tube in any desired way such as by means of packing 70 nuts 35.

75 The arrangement of the fuel pipe 24 and the compressed air pipe or tube 30 forms an important feature of the invention and particular attention is invited to the arrangement of the fuel feed tubes 36 with the nozzle 31, which are carried by the upper end of the fuel pipe 24. These fuel tubes 36 are of relatively fine diameter and are threaded into the upper end of the fuel tube and terminate in close proximity to the outlet of the air nozzle 31.

80 Arranged within the casing 20 above the fuel pipe 24 and air nozzle 31 is a Venturi tube 37 which forms one of the salient features of this invention. The tube 37 is arranged axially within the casing and is connected with a sleeve 38 by means of arms 39. This sleeve 38 snugly engages the wall of the casing and is adjusted relative to the nozzle 31 and fuel tube 36 according to the type of 85 the engine with which the carburetor is associated and the quality of the fuel being used. This sleeve can be held in adjusted position in any desired way and I have shown a set 90 screw 40 for this purpose.

95 The tube is provided with an axial bore and the lower end of this bore is of a conical shape as indicated by the reference character 105 41 with its flared end lowermost. This flared portion of the bore extends over one half of the height of the tube and terminates in a straight bore or restricted neck portion 42. This straight bore or restricted neck portion 42 in turn opens into a flared portion 43 110 which gradually increases in diameter. This portion 43 gradually increases in diameter and in turn communicates with a flared portion 44 which extends the extreme outer edge of the tube at the upper end thereof. I lay 115 particular stress on the conical portion 43 and the enlarged conical portion 44 which is of a substantially saucer shape, as by the shape and arrangement of the portions 43 and 44 I obtain an action on the fuel which is 120 essential to the operation of the carburetor.

125 The fuel tube 24 extends above the normal fuel level in the float chamber 10 and when the carburetor is in action, the flow of the compressed air out of the nozzle 31 serves as means for lifting the fuel up in the fuel tube and into the tube 37.

130 The suction of the engine acting in the carburetor draws the air into the carburetor around the choker valve and up into the cas-

ing so that the same will circulate around the fuel tube and the Venturi tube 37.

In operation of the carburetor the suction also acts in the Venturi tube and the conical flared portion 41 functions as means for receiving the fuel into the tube 37 from the fuel outlet tubes 36. As the compressed air and fuel flows into the restricted neck or straight bore 42 the same is combined and this constitutes a function of the Venturi tube. As the fuel and compressed air flows out of the restricted neck 42 the same engages the gradually flared or conical portion 43 and then passes into the flared or saucer shaped portion 44 of the tube. The peculiar shape of the portion 44 and the action of the fuel and air as the same leaves the conical portion 43 serves as means for spreading the fuel and compressed air out into the air stream. The fuel is broken up into minute particles and leaves the tube in the nature of a fine atomized whirl. This insures the proper mixing of the fuel and air and explosion of the mixture will be substantially instantaneous in the cylinder.

A throttle valve 45 is rockably mounted in the casing above the tube 37 and is controlled in any desired way at a point distant from the carburetor. The flow of air and fuel through the casing is substantially uninterrupted and is only controlled by the choker valve 23 and throttle valve 45.

I also provide a manually controlled reducing valve 46 in the air line which provides means for regulating and controlling the air pressure at the nozzle so that the compressed air can be conveniently handled for different qualities of fuel.

The flared lower end 41 of the triple tube 37 also forms means for preventing the spreading of the air from the nozzle 31. As stated the narrow or small part 42 of the tube restricts the passage of both fuel and air and causes the force of the particles of air in motion to separate the particles of fuel to very fine particles. The pressure of the air is such so that the friction of the fuel and air passing through the restricted passage 42, will be just under the point of combustion.

In Figure 5 I have illustrated a slightly modified form of fuel outlets and in this form, I provide a plurality of fuel tubes 46 which are connected with the fuel pipe 24 in the same manner as the tubes 36. These tubes 46 are of different diameters and different lengths and it is to be noted that the tubes having the smallest diameter terminates in closest proximity to the outlet of the nozzle 40 while the tube having the greatest diameter terminates furthest from the outlet of the nozzle. By this arrangement when the suction in the carburetor is low only the tube 46 will be brought into play, but as the speed of the engine increases and the suction rises one

tube after the other will be brought successively into play until all the tubes including the tube having the greatest diameter are in operation. Thus in this form the flow of the fuel is automatically governed according to the speed of the engine.

Changes in details may be made without departing from the spirit or scope of the invention, but

What I claim as new is:

1. In a carburetor, a casing having an air way therethrough, a compressed air feed pipe leading into said air way, a nozzle on said pipe disposed axially within said way, a plurality of fuel tubes grouped about said nozzle, the tubes being of different diameters and terminating at different points relative to the outlet of the nozzle, the tube having the smallest diameter terminating nearest the outlet of the nozzle and the tube having the greatest diameter terminating furthest from the outlet of the nozzle.

2. In a carburetor, a casing having an air way therethrough, a choker valve for controlling the flow of air through the way, a fuel pipe extending axially in the air way, means for maintaining a predetermined level of fuel in the pipe, a compressed air feed pipe extending axially through the fuel pipe and terminating above the same, the fuel pipe having snug engagement with the air feed pipe at the upper end thereof, a nozzle on the upper end of the air feed pipe, a plurality of fuel tubes communicating with the fuel pipe and terminating in close proximity to the outlet of the nozzle and grouped about the same, and a Venturi tube arranged above the nozzle and fuel tubes and disposed axially in the airway, said venturi having means for restricting the flow of the air from the nozzle, means for combining compressed air and fuel, and means for spreading the fuel and compressed air outwardly in the airway.

In testimony whereof I affix my signature.

AMBROSE C. DE LANGE.
